UNITED STATES PATENT OFFICE

161,733

DESK

De Lois J. Burchard, Russellville, Ark.

Application December 10, 1949, Serial No. 6,540

Term of patent 3½ years

(Cl. D33—7)

To all whom it may concern:

Be it known that I, De Lois J. Burchard, a citizen of the United States, residing at Russellville, in the county of Pope and State of Arkansas, have invented a new, original, and ornamental Design for a Desk, of which the following is a specification, reference being had to accompanying drawing, forming part thereof.

I claim:

The ornamental design for a desk, as shown.

DE LOIS J. BURCHARD.
